UNITED STATES PATENT OFFICE

151,984

DESIGN FOR A COMBINATION CIRCULAR HASSOCK AND COFFEE TABLE

Gabriel C. Guertin, Boston, Mass.

Application April 10, 1947, Serial No. 138,281

Term of patent 3½ years

(Cl. D15—8)

To all whom it may concern:

Be it known that I, Gabriel C. Guertin, a citizen of the United States, residing at Boston, in the county of Suffolk and Commonwealth of Massachusetts, have invented a new, original, and ornamental Design for Combination Circular Hassock and Coffee Table, of which the following is a specification, reference being had to the accompanying drawing, forming part thereof.

In the drawings,

Fig. 1 is a perspective view of a combination circular hassock and coffee table showing my new design, and

Fig. 2 is a similar view showing separable parts of the hassock in open position to expose the coffee table.

All three legs of the coffee table extend beyond the lower circular shelf of said table in the same manner as the table leg illustrated in the foreground of Fig. 2.

I claim:

The ornamental design for a combination circular hassock and coffee table, substantially as shown and described.

GABRIEL C. GUERTIN.
